UNITED STATES PATENT OFFICE.

RUDOLPHE W. E. CHRISTESEN, OF NEW BRITAIN, CONNECTICUT.

DESIGN FOR A GONG FOR BELLS.

SPECIFICATION forming part of Design No. 30,429, dated March 28, 1899.

Application filed February 18, 1899. Serial No. 706,083. Term of patent 3½ years.

To all whom it may concern:

Be it known that I, RUDOLPHE W. E. CHRISTESEN, a citizen of the United States, and a resident of New Britain, in the county of 5 Hartford and State of Connecticut, have invented and produced a new and useful Design for Gongs for Bells, of which the following is a specification, reference being had to the accompanying drawings, forming a part 10 thereof.

Figure 1 is a top or plan view of a gong for a bell, showing my new design. Fig. 2 is a view in side elevation of the gong.

My invention is embodied in the class of 15 bells known as "bicycle-bells," which as to general shape and outline are well known; and in such form of bell I embody on the rounded upper surface *a* of the gong, which is curved in outline, as shown in plan view, the representation of a conventional cupid, shown in 20 relief. As shown in side elevation, as seen in

Fig. 2, the upper part of this gong is rounded, and it has as a whole a somewhat hemispherical shape. The cupid is represented as holding in its hands a musical instrument *c*, and 25 surrounding the figure is a background of rococo ornamentation *d*, the edges of the mass forming a species of border.

The material feature of my design is the gong displaying the conventional figure of a 30 cupid and surrounded by conventional ornamentation.

Having described my invention, what I claim as new, and desire to secure by Letters Patent, is—

35 The design for a gong for a bell substantially as herein shown and described.

RUDOLPHE W. E. CHRISTESEN.
